CONSTRUCTION OF SHOE SOLES OF WOOD
OR OTHER STIFF MATERIALS

Henry Ghez and Oscar Ghez, New York, N. Y.

Application June 2, 1942, Serial No. 445,434

12 Claims. (Cl. 36—33)

This invention relates to certain features of construction of soles for boots, shoes, clogs and sandals, etc., which are made of wood or other normally stiff materials and are slotted or cut to impart resiliency, flexibility or actual articulation, as disclosed in our copending applications, Serial Nos. 431,776 filed February 21, 1942; 438,598 filed April 11, 1942; 438,599 filed April 11, 1942, and 443,648 filed May 19, 1942.

The main object of our invention is to provide soles of the indicated character with more or less flexible blinding or connecting members serving to hold articulation or flexure of the soles within safe limits and/or to form means upon said soles to which an upper may be sewed.

Another object is to increase the usefulness of such soles and make them more readily available for general adoption by manufacturers and the public.

A further object is to make it practical to use wood or other stiff and/or cheap materials for soles in order to economize on rubber and leather and still produce large quantities of excellent footwear.

It is also an object herein to speed up production and lower costs in the manufacture of such footwear.

It is likewise an object to introduce a series of new designs in soles and footwear embodying the same by virtue of the construction and features of said soles.

Other objects and the advantages of our invention when applied to footwear generally will appear more fully as this specification proceeds.

In order to disclose more comprehensively the salient features of the invention, certain forms thereof are illustrated in the accompanying drawings forming part hereof, the same showing,

In Fig. 1, a bottom plan view of a sole made according to certain principles of our invention.

Fig. 2 is a side elevation of the same in normal position.

Fig. 3 is another side elevation showing the sole in extreme flexed condition.

Fig. 4 is a cross section of the sole taken on line IV—IV in Fig. 1.

Fig. 5 is a bottom plan view showing a modification of the sole of Fig. 1.

Figs. 6 and 7 are similar views of two further modifications.

Fig. 8 is a side elevation showing a modification of the sole of Figs. 1 to 5.

Fig. 9 is a top plan view of a different modification of the sole of Fig. 1.

Fig. 10 is a transverse section of the sole of Fig. 9 on an enlarged scale.

Figs. 11 and 12 are also sections of modifications of the sole of Figs. 9 and 10.

5 Figs. 13 to 17 in similar fashion, are further modifications.

Throughout the views, the same references indicate the same or like parts.

In connection with footwear, it is desirable to have flexible soles capable of flexing with the feet in walking, and for the soles, leather, rubber, fabric and felt, etc., are commonly used. However, it has been disclosed in our mentioned copending applications that normally stiff or more or less rigid materials such as wood, plastics, metals, etc., may be made flexible in structure by cutting slots through the same part way alternately from one edge toward the other, each of the resulting sections of the sole being slightly flexible, with the flexibility of all the sections in a series summing up to a satisfactory and sufficient flexibility of the sole as a whole.

20 The present invention preferably refers to improvements in the mentioned type of flexible sole while keeping the foregoing objects in mind.

Hence, referring now again to the drawings, a sole, generally indicated at 1 in Figs. 1 and 2 is preferably made of wood, more or less rigid plastic material or composition, or even metal, such as, 30 steel, brass, beryllium copper, or aluminum, etc., and has a series of slots 2, 3, etc., alternately extending inwardly from the opposite edges 4 and 5 of the sole proper, said slotted condition not extending necessarily to the shank 6, nor to the heel 7, although they could well do so upon occasion if found desirable. The purpose of the slotted condition of the sole is to allow flexure thereof as shown in Figure 3, for example, although said sole is made of normally rigid material. Each slot allows the section between the same and the next adjacent slot to twist or bend slightly and when the sole has a large number of such slots the sum total of the torsion of all the bent portions amounts to a sufficient and entirely satisfactory flexure of the sole, the upper edges of the slots tending to meet while the lower edges are separated further in flexed condition of said sole. The foregoing features are already disclosed in our copending applications but are merely mentioned to form a proper background for the present invention.

55 It is quite evident that if a slotted sole should be entirely dissociated from other elements it could be flexed beyond safe limits so as to reach a point of fracture when one or more of the sec-

tions thereof would break and the sole immediately be ruined. One of the objects of this invention is therefore to apply to the sole certain means which will limit flexure within a safe range and also upon occasion serve as proper welt means to which an upper may be sewed or attached when properly located upon a sole.

As particularly shown in the first two views already referred to, a rand 8 of leather, rubber, or synthetic plastic of the vinylite series for example may be cemented, nailed, or riveted to the sole 1, preferably on the bottom thereof and may either be directly applied to the bottom surface or placed in a recess 9 cut into the bottom about the edges thereof. Upon comparing the normal unflexed condition of the sole in Figure 2 with the flexed condition particularly shown in Figure 3, it will be immediately apparent that the rand 8 limits the separation of the lower edges of the slots 2 and 3 and prevents further separation thereof, while the upper edges are free and may be caused to approach each other so that each slot in cross section will present a form similar to an inverted V. Flexure of the sole thus is limited to the amount of approach occurring between the upper edges of the slots within the range of the tensile strength of the rand 8 and beyond extreme flexure as shown no further change of shape can occur. In view of the limitation of the flexing of the individual sections of sole 1, breakage will not occur as the sole is not flexed beyond a useful limit thus provided by the rand 8. While the sole 1 is substantially the same in Figures 5 through 8 as in Figures 1 to 4 and the slots and other features of said sole remain practically the same, it is referred to in the same fashion as in the first four figures. In Figure 5 the rand 8 of horseshoe shape has been replaced by two short rands 10 and 11, preferably located in recesses at the sides of 4 and 5 of the bottom of sole 1, the principle of limiting the flexure of the sole remaining exactly the same. In the same manner as the rand may vary by having the horseshoe form or by subdividing into two members, the slots 2 or 3 may likewise vary in number and spacing. It is evident that only one of the rand members 10 or 11 may be used alone if desired. The shape of this rand may vary not only in length but in contour.

In Figure 6 the V-shaped leather, rubber or plastic member 12 preferably occupies a recess portion in the bottom of the sole. No portion of this member, which actually forms a limiting reinforcement extends out to the edges 4 and 5 of the sole, but is wholly located within the outline thereof, while serving the same purpose as rand 8 or members 10 and 11 in the preceding figures.

Another form of the reinforcing member is shown in Figure 7 at 13 where the same is a strip running down through the center of the sole proper and also being spaced at all points within the edges 4 and 5 of the sole.

It is clear that the reinforcing member not only may assume various shapes, but may also be located in some other position than upon or in the bottom of the sole, and may therefore be inserted intermediately between the bottom 14 and top 15 of the sole 1 of Figure 8. The reinforcing member 16 in this figure either takes the form of the horseshoe shaped rand 8 of the first two figures or extends entirely through the sole from side to side. In any event said rand 16 occupies an intermediate slot 17 in the sole, said slot being either of limited depth from the edges

or else extending through the sole so as to subdivide the same into upper and lower halves, either of these forms being obvious from Figure 8. The reinforcing member may have its usefulness extended into the very method of assembling the shoe or other footwear for which the sole is to be used, but being modified to form or occupy a sufficient amount of the peripheral edge of the sole to allow sewing the upper therethrough, one form of the sole in such condition being shown in Figures 9 and 10. Thus the sole 17 which is of more or less stiff or rigid material as in the case of sole 1 of former figures is also slotted as indicated at 18 and 19, etc., while both the upper and lower surfaces 20 and 21 are recessed about the edges at 22, 23, and each of the recessed portions provided individually with rands 24 and 25 of rubber, leather, felt, or plastic of the vinyl series, these rands being secured in place upon the sole by means of nails, rivets or cement. The contour of the sole proper is reduced in size by cutting away a marginal portion thereof so as to allow for the width of a filler between rands 24 and 25 in the form of a band 26 of felt, rubber, plastic, or other suitable material, the same being secured in place between said rand members by cement or any other means known in the art. The upper partly indicated at 27, 27 may be sewed to the resulting reinforcing member or assemblage generally indicated at 28 by stitches 29, 29, although it could be wired or wire-sewed to the assemblage 28 if desired.

In Figure 11 the sole 17 is substantially the same in every detail but the assemblage 28 of Figures 9 and 10 has been replaced by a single channel-shaped marginal reinforcement 30 which is nailed, riveted or cemented to the sole, while the upper 27, 27 is sewed thereto by stitches 29, 29 as before.

In Figure 12 the sole 31 preferably made of the same material as soles 1 or 17, has an upper rand 32, a filler band 33 while an outer wearing sole 34 is applied to the bottom and extends the entire width of the sole and the marginal members 32 and 33, and is cemented, nailed or otherwise secured to the sole, and is also true of members 32 and 33 while the upper 27, 27 again is sewed to the assemblage formed by said parts 32, 33 and 34.

It is quite possible to confine the rand to the top of a sole as particularly shown in Figures 13 through 17, the sole 35 in Figure 13 having an upper rand 36 seated in a recess 37 in the upper marginal edge thereof, while a cut-away portion 38 is formed with the main clearance thereof occurring toward the top adjacent to the bottom of rand 36 in order to allow clearance for the stitching of the upper 27 thereto as indicated at 39.

In Figure 14 another form of clearance for the sewing of the shoe upper to the welt or rand is shown upon the sole 40 which has a groove or channel 41 within the edges of the upper surface 42, the rand 43 itself being secured by nails, screws or cement to the sole and accommodated in a recess 44. The upper 27 is sewed to the rand or welt at 45 immediately over the center of the channel 41 so that during stitching or sewing the needle will have the best possible clearance below without actually overhanging the outer periphery of the sole.

Another form which provides clearance for the sewing is shown in Figure 15 wherein the sole 46 has a rand or welt 47 occupying a recess 48 in the upper edge of the sole, while extending out

beyond the outer edges to a limited distance in order to provide a full width for the sole. Co-operating with the welt or rand 47 is an outer band or rim 49 which is secured directly to the side edges 50 of the sole by nailing or cementing the same, while the upper portion of said band is bent outwardly to lie against the lower portion of the outer edge of rand 47 and may be made of leather, rubber, plastic or even felt, etc. The upper 27 is sewed to the rand 47 and also to the band or lower welt 49 as shown at 51.

Another modification of reinforcing and/or attachment means shown in Figure 11 is illustrated in Figure 16, wherein the sole 52 has a peripheral projection 53 about the edges thereof, which is undercut both above and below and extends into an undercut groove or channel in the solid rand 54 and is preferably cemented in place so that once assembled this rand is substantially rigid with the sole 52 although it is itself composed of more or less resilient material, the upper 27 being sewed thereto at 55.

A reversal of the structure of Figure 16 is shown in Figure 17, where the sole 56 has a dovetail or undercut slot, channel or groove 57 in the peripheral edges thereof into which a tongue member or bead 58 of a solid rand 59 is fitted, the upper 27 being sewed to said rand at 60.

In all the various forms or modifications of the invention one feature appears in common and throughout, namely, that the rand or one or more welts, bands, connecting or reinforcing means used in every case bridges the slots between the various sections of the sole so as to limit flexure thereof within a safe range and in all cases connects the slotted sections together. The material of the sole itself being for this purpose of less importance than the material of which the welt, rand, reinforcing means, etc., may be made, as for the latter it is possible to use various fabrics, felt, synthetic or natural rubber, plastic materials, skin and leather in any combination desired. It should also be stated that the rand reinforcing member or the like may extend a limited distance along the sides of the sole or in any position upon the same, bridging or at least connecting the slotted sections, or may extend around the entire periphery of the sole and heel, being perhaps modified at the heel in order to provide at least upper rand means for sewing the upper thereto.

While various other modifications and related structures may be suggested, it is particularly emphasized that the forms shown are merely presented as practical examples and illustrative of an entire series of constructions embodying similar principles and we therefore reserve any and all embodiments of these principles as commensurate with this specification so that the invention extends to all such forms within the scope of the appended claims.

Having now fully described our invention, we claim:

1. An outer sole for footwear made of a material normally relatively stiff, hard or inflexible and rendered flexible by the provision of a series of slots extending substantially transversely from near one edge of the sole across only a major part of the width of the sole and a second series of similar slots extending from near the opposite edge of the sole and extending across only a major part of the width of said sole, the slots extending through the entire thickness of the sole so as to provide a series of resilient sole sections, and flexible elongated means attached to said sole and

interconnecting the slotted sections thereof so as to bridge the slots between said sections.

2. An outer sole for footwear made of a material normally relatively stiff, hard or inflexible and rendered flexible by the provision of a series of slots extending substantially transversely from near one edge of the sole across only a major part of the width of the sole and a second series of similar slots extending from near the opposite edge of the sole and extending across only a major part of the width of said sole, the slots extending through the entire thickness of the sole so as to provide a series of resilient sole sections, and flexible elongated means attached to a portion only of said sole substantially lengthwise of the same, and interconnecting slotted sections thereof so as to bridge the slots between said sections.

3. A sole according to claim 1, in which the flexible elongated means comprising a rand of flexible material of the class consisting of fabric, felt, leather, rubber and plastic extending along at least a part of the periphery of the sole.

4. A sole according to claim 1, in which the flexible elongated means comprising a rand of flexible material of the class consisting of fabric, felt, leather, rubber and plastic extending along at least a part of the periphery upon the bottom of the sole.

5. A sole according to claim 2, in which the flexible elongated means comprising a rand of flexible material of the class consisting of fabric, felt, leather, rubber and plastic extending along at least a part of the periphery in a slot intermediate the upper and lower surfaces of the sole.

6. A sole according to claim 2, in which the flexible elongated means comprising a rand of flexible material seated in a recess upon the bottom of the sole.

7. A sole according to claim 2, in which the flexible elongated means comprising a welt or rand of flexible material of the full height or thickness of the sole and having portions of both sole and rand mutually engaged and secured together.

8. A sole for footwear made of material which is normally stiff, inflexible and hard and rendered flexible and supple by the presence of a plurality of spaced open slots in said material extending completely through the sole from one edge a distance toward but not to the other edge so as to provide a series of resilient sole sections, said sole having a generally horizontal open slot extending at least partially thereacross and dividing the larger part of said sole into upper and lower halves, and a rand of flexible material in said slot secured to and interconnecting the upper and lower halves and interconnecting the slotted portions thereof so as to bridge the slots.

9. A sole for footwear made of a material which is normally stiff, inflexible and hard and rendered flexible and supple by the presence of a plurality of spaced slots in said material extending completely through the sole from one edge a distance toward the other edge so as to provide a series of resilient sole sections, and elongated flexible means attached to a portion only of said sole and interconnecting the slotted sections thereof in said portion, elongated means comprising a rand of flexible material of the class consisting of fabric, felt, leather, rubber and plastic, extending along at least a part of the periphery and having at least a portion thereof in a slot intermediate the upper and lower surfaces of the sole.

10. An outer sole for footwear made of a ma-

terial normally relatively stiff, hard or inflexible and rendered flexible by the provision of a series of slots extending substantially transversely from near one edge of the sole across only a major part of the width of the sole and a second series of similar slots extending from near the opposite edge of the sole and extending across only a major part of the width of said sole, the slots extending through the entire thickness of the sole so as to provide a series of resilient sole sections, an elongated flexible means secured to and co-extensive with a limited portion of said sole and interconnecting the slotted sections thereof so as to bridge the slots between said sections in said portions.

11. An outer sole for footwear made of a material normally relatively stiff, hard or inflexible and rendered flexible by the provision of a series of slots extending substantially transversely from near one edge of the sole across only a major part of the width of the sole and a second series of similar slots extending from near the opposite edge of the sole and extending across only a major part of the width of said sole, the slots extending

6 through the entire thickness of the sole so as to provide a series of resilient sole sections, the lower peripheral edge of said sole being cut away to provide a generally rectangular recess on each side of said sole, and a generally rectangular rand of such material in said recess on each side of said sole and interconnecting the slotted portions thereof so as to bridge the slots.

10 12. An outer sole or the like for footwear comprising, the combination of a main body member of normally stiff material having the outline of at least a half sole and a series of transverse slot portions cut entirely through said body alternately from each side edge across a major portion thereof toward the opposite side edge, and a rand or marginal strip of elastic material of the class consisting of rubber, vinyl plastics and other resilient plastics occupying a perimetral recess in the edge of the lower surface of the body member so as to bridge the outer ends of said slot portions.

15 20 HENRY GHEZ.
OSCAR GHEZ.
